UNITED STATES PATENT OFFICE.

JACOBY IMBRUGLIA, OF ALAMEDA, CALIFORNIA.

WINDOW SCREEN.

Application filed July 17, 1926. Serial No. 123,178.

My invention relates to a window screen, and particularly to a combined draft and fly screen of adjustable length arranged to be removably installed in windows equipped 5 with lift sashes.

An object of the invention is to provide a screen of the type described which, when mounted in a window frame, prevents the horizontal passage of a draft of air into a 10 room and at the same time provides the necessary ventilation for the room.

Another object of the invention is to provide a screen of the type described having its parts unitarily associated, and so arranged 15 as to be foldable to occupy a minimum of space when not in use.

The invention possesses other objects and features of advantage, some of which, with the foregoing, will be set forth in the following 20 description of the preferred form of my invention which is illustrated in the drawings accompanying and forming part of the specification. It is to be understood that I do not limit myself to the showing made by 25 the said drawings and description, as I may adopt variations of the preferred form within the scope of my invention as set forth in the claims.

Referring to said drawings, 30 Figure 1 is a perspective view showing the screen of my invention operatively mounted in a window.

Figure 2 is a plan view of the screen mounted in a window.

Figure 3 is a perspective view showing the screen folded.

As herewith particularly illustrated, the screen 4 of my invention is mounted in a window frame 6 between the side stops 7, 40 the sill 8, and a sash 9 movable vertically in a guideway 11 defined between outer stops 12 and the stops 7 of the frame. When it is set up, the screen presents an outline which is generally that of a triangular prism with 45 one longitudinal side horizontally disposed, another side obliquely disposed, and the third side vertically disposed in the plane of movement of the sash 9. Furthermore, to provide for its use in windows of various widths, the 50 screen is preferably formed with sections 13 and 14 engaged for telescopic engagement longitudinally of each other.

As here shown, the horizontal sides 16 and 55 17 of the sections 13 and 14, respectively, comprise frames 18 and 19 in which are mounted perforated panels 21 and 22, the lat-

ter being here shown formed of wire screen, preferably of such mesh as to prevent the passage of flies and the like therethrough. The oblique sides 23 and 24 of the sections 60 13 and 14 respectively are preferably imperforate and respectively carry the frames 18 and 19 hingedly connected thereto at their top edges, it now being noted that the frame 18 engages telescopically in guideways provided on the side edges of frame 19, and is arranged for movement above the plane of the latter, while the side portion 23 lies inwardly 65 of the side portion 24 and engages telescopically in guideways provided at the top and 70 bottom edges of the latter.

Preferably hingedly secured to the opposite ends of sides 23 and 24 are triangular and preferably imperforate members 26 and 27 which are arranged, when appropriately 75 swung to extend outwardly of the sides 23 and 24, to provide end walls for the screen, the top edges thereof being arranged to underlie and provide a support for the ends of the frames 18 and 19 respectively. The end 80 walls 26 and 27, it will now be noted, are here shown provided with outwardly extending flanges 28 arranged to engage against and along the pair of window stops 7 defining the inner side of the sash guideway 11, 85 and are preferably provided at their upper edges with inwardly extending flanges 29 underlying the top frame ends 31. The flanges 29 and ends 31 are correspondingly 90 perforated to receive fastening pins 32, the latter being here shown as screw headed bolts arranged for threaded engagement in the perforations of the flanges 29 so that the 95 section ends may be releasably secured to the top ends 31 to rigidly hold the sections in fixed relation.

It will now be noted that with the sections telescopically engaged and so positioned as to allow the insertion of the vertical stop engaging flanges 28 in the plane of movement 100 of the sash, the sections may then be spread apart to bring their end walls against the opposed surfaces of the stops 7. With the lower edge 33 of the oblique wall seated on the sill 8, the sash 9 may then be moved downwardly 105 to register with the top of the screen structure, it being noted that the outer edges 34 and 36 of the top frames 18 and 19 are preferably arranged to extend only to the plane of movement of the sash, so that the sash may 110 be raised or lowered while the screen is operatively disposed at the window.

With the screen positioned in the window as described and the various joints between the parts made substantially air tight, it will now be obvious that a stream of air flowing through the screen will of necessity be forced to flow in an oblique direction through the perforated panels, thus preventing a direct flow of air to or from the opening defined below the sash. Furthermore, it will be noted that the device may be mounted to extend outwardly of the room, the flanges 28 being engaged against the stops 12. However, in rainy weather, the inward positioning of the screen will be necessary, it being noted that any rain blown inwardly below the open sash will be caught on the oblique side portions 23 and 24 and so be directed downwardly and outwardly of the window.

Means are preferably provided for urging the section ends to maintain their position against the window stops. As here shown, such means comprises one or more tension springs 37 fixed to and between the inner extremities of the sections so that the latter are urged to maintain an outward telescopic relation.

It will now be noted that the screen may be folded up by removing the pins 32, folding the ends 26 and 27 against the outer surfaces of the sides 23 and 24 to which they are respectively attached, and folding the frames 18 and 19 against the opposite surfaces of the same sides. If desired, the springs 37 may also be released at one end to permit the inward telescoping of the section. In this manner the screen is foldable into a flat package for ready transportation or storage.

It will, of course, be obvious that the device herein described may be used solely for ventilating purposes, in which event the per-

forated panels in the frames 18 and 19 might be dispensed with.

I claim:

1. A window screen arranged to be disposed in a window opening providing a guideway for a displaceable sash and comprising an imperforate longitudinal wall, end walls pivotally secured to said first wall, a perforate longitudinal wall pivotally secured to an edge of said first wall, means releasably connecting said end walls and perforate wall whereby a fixed relation of said walls will be maintained, means carried by said screen and engageable in said guideway for securing the screen in operative position in said window opening, and means carried by said screen resiliently maintaining said last means operatively disposed. 45 50 55

2. A window screen arranged to be disposed in a window opening providing opposed guideways for a displaceable sash, comprising a pair of telescopically engaged sections, each of said sections comprising an obliquely disposed imperforate wall, a vertically disposed end wall hinged to the first wall at the outer end thereof, and a horizontally disposed perforate wall hinged to the first wall at the top edge thereof and arranged to overlie and be fixedly secured to the top edge of the end wall, means carried by each section engageable in a different one of said guideways for securing the screen in operative position in the window opening, and means cooperating between said sections to resiliently urge them apart and into operative engagement with said guideways. 60 65 70 75

In testimony whereof, I have hereunto set my hand at Oakland, California, this 29th day of June, 1926.

JACOBY IMBRUGLIA.
